UNITED STATES PATENT OFFICE.

WILL P. DAHL, OF MINNEAPOLIS, MINNESOTA.

GAS-PLIERS.

SPECIFICATION forming part of Letters Patent No. 356,241, dated January 18, 1887.

Application filed November 2, 1886. Serial No. 217,802. (No model.)

To all whom it may concern:

Be it known that I, WILL P. DAHL, of Minneapolis, in the county of Hennepin and State of Minnesota, have invented a new and useful 5 Improvement in Gas-Pliers, of which the following is a full, clear, and exact description.

This invention relates to pliers; and it consists, essentially, of a combination tool embodying pliers having variously-sized jaws applicable for use in connection with varying parts of a gas-fixture, a wire-cutting attachment, a lava-tip-turning attachment, a band adapted for use in the cleaning of the slots of the lava tips, a screw-driver, and a stop-cock 15 or valve-turning recess.

Reference is to be had to the accompanying drawings, forming a part of this specification, in which similar figures of reference indicate corresponding parts in all the views.

20 Figure 1 is a side view of my improved form of pliers, a portion of one of the lever arms or handles being shown in section to disclose the arrangement of the lava-tip-cleaning strip, the pliers in Fig. 1 being represented as they appear when opened. Fig. 2 is a side view of the pliers, representing them as they appear when closed. Fig. 3 is a perspective view of one section of the pliers; and Fig. 4 is a view of the inner face of one of the lever arms or 25 handles of the pliers, representing the lava-tip cleaner as it appears when arranged within a recess formed within said arm.

In the drawings above referred to, 10 and 11 represent the two sections of the pliers, said 30 sections being united by a rivet or bolt, 12, the central joint being made in the ordinary well-known way. The jaws 13 and 14 are each formed with concave serrated recesses 2 and 3, the recesses of each jaw being arranged to register, as shown in Fig. 2. The recesses 3 are 35 provided for use upon the burners proper, while the recesses 2 are arranged for turning the globe and fixture screws.

In the extreme end of each jaw there is formed 40 a serrated recess, 4, back of which there is a semicircular flange, 5, and between the flange 5 and the recess 2 there is a plain-faced recess, 6, the recesses 6 being so formed and proportioned that when serrated faces of the recesses 4 are brought into engagement with the tops

of the burners the lava tips carried by the burners will pass upward through the central apertures of the flanges 5 and enter the recesses 6. These lava tips may be brought into the bite of the flanges 5 and so forced within 55 their sockets.

Each section of the pliers is formed with a slot, 9, of which the edge 8 is a cutting-edge, the arrangement being such that when the pliers are open to the position in which they are 60 shown in Fig. 1 and a wire is introduced within the slots 9 when the pliers are closed the wire will be caught between the cutting-edges 8, and will consequently be sheared or cut in two.

As the handles of the pliers approach the 65 pivot pin or bolt 12 they are cut out, so that their edges 16 will be parallel when the jaws of the pliers are brought together, thus providing for the reception of the thumb-piece or handle of the stop-cock or valve of the gas- 70 fixture, thereby enabling the operator to secure a sufficient amount of leverage to turn any stop-cock or valve that may happen to become bound.

The rear end of one of the handles is provided with a projecting point, 17, which is arranged for use as a screw-driver. This screw-driver will be found convenient in removing or loosening the nut under the core. 75

In connection with the parallel face 16, in the 80 inner face of the other handle of the pliers I arrange a recess, 18, across which there is secured a retaining band or plate, 19, and in this recess 18 I mount a spring-strip, 20, which is provided with a handle or knob, 21, the arrangement being such that the strip may be forced outward in the direction of the arrow shown in Fig. 1, and so constitute an attachment for the pliers, which may be used to clean out the slits or slots of the lava tips. 90

Such an implement as I have described will be found to be exceedingly convenient and useful in the fitting of gas-fixtures, and as each section of the pliers may be made in the same die the cost of manufacture is reduced to a minimum. 95

Having thus fully described my invention, I claim as new and desire to secure by Letters Patent—

1. As a new article of manufacture, gas- 100

pliers formed with transverse recesses 2, 3, and 6, longitudinal recesses 4, and cross-flanges 5, substantially as described.

2. As a new article of manufacture, pliers formed with serrated recesses 2 and 3, a serrated recess, 4, a recess, 6, arranged between the recesses 2 and 4, and slots 9, having cutting-edges 8, substantially as described.

3. As a new article of manufacture, pliers

formed with recesses 2, 3, 4, and 6, slots 9, and 10 parallel faces 16, and provided with a spring-strip, 20, that is mounted within a recess formed in one of the handles of the pliers, substantially as described.

WILL P. DAHL.
